Attest.

with a pulley 31 which is secured thereon by a set screw 32. The pulley 31 is connected in driving relation by a belt 33 with an eccentric pulley 34. The eccentric 34 is provided with a bearing receiving recess in its upper face which receives a bearing 35 secured on a stub shaft 36. The shaft 36 depends from the upper rear wall portion 37 of the casing member 11 and is secured thereto by the screw 38. The pulley 34 is provided with a depending eccentric shaft portion 39 which projects into a pocket or recess 40 in a connecting yoke member 41 and is secured therein by a bearing 42 which is fitted over the eccentric 39 and into the pocket 40.

The connecting yoke 41 is of relatively rigid material and generally Y-shaped. It is arranged in parallel relation to the rubbing shoe 22 and is secured thereto at three points by resilient blocks 43. Each of the blocks 43 is formed of rubber or similar resilient material and provided with a metal anchor plate 44 in its upper face and a similar anchor plate 45 in its lower face. The anchor plates 44 and 45 are vulcanized or otherwise securely fastened to the blocks 43. The blocks 43 are secured at the ends of the legs of the member 41 and to the plate member 24 by screws 46 and 47 in threaded engagement in the apertures in the anchor plates 44 and 45. Blocks 43 resiliently connect the yoke member 41 in spaced relation to the rubbing shoe 22 with the center of the pocket 40 and the bearing 42 connecting the same to the eccentric portion 39 of the pulley 34 located farther toward the rear end of the machine than the front end of the same.

The rubbing shoe 22 is preferably provided at its ends with clamping means for securing in position thereon the abrasive coated member 23. The illustrated securing means comprises a rubber covered roller 48 arranged adjacent each end of the plate 24. The rollers 48 are each mounted on a shaft 48' and held in position by a pair of spring members 49 which are secured adjacent the sides of the plate member 24 by rivets or other securing means 49' at one end thereof. At the other end the spring members 49 are each provided with a curved retaining portion 49'' accommodating the projecting end of the shaft 48' of the roller 48. One outer end of each roller shaft 48' may be conveniently formed with a slot 48''' for receiving a screw driver to permit the clamping rollers 48 to be rotated in frictional engagement with the turned over ends of the abrasive member 23 to secure the same in clamping relation on the top of the plate 24. The shaft end may be recessed or provided with any suitable end formation to accommodate any other form of turning tool.

In operation the power driven shaft 14 rotates the pulley 34 by means of the belt 33 which imparts an eccentric movement to the bearing 42 and the member 41 by reason of the connection with the eccentric portion 39. The movement of the member 41 is transmitted through the resilient connecting pads 43 to the shoe 22 which carries the abrasive or rubbing member 23. Due to the resiliency of the connecting blocks 43 the movement of the shoe 22 is irregular and varies with the pressure applied against the work and other factors, such as the nature of the rubbing surface and the nature of the material being worked, which effect resistance to the motion of the member 41. Portions of the rubbing pad or shoe may vibrate in a longitudinal direction while other portions may simultaneously vibrate in a transverse direction or diagonally relative to the supporting casing 11. The vertical thrust caused by engaging the shoe 22 with the work is absorbed by the resilient connecting posts 27 and the resilient connecting pads 43 without damage to the vibrating mechanism connecting the member 41 with the power shaft 14.

Referring to Figs. 4 to 6, there is illustrated a modified form of the machine which comprises the downwardly opening supporting frame or casing member 50 and a plurality of resilient depending connecting posts 51 which support thereon a work element carrying pad or shoe 52. The shoe 52 is adapted to vibrate against the resistance of the connecting elements or posts 51 in any direction relative to the supporting casing 50. A motor housing 53 in which the motor 54 is supported is arranged above the casing member 50 with the motor shaft 55 depending therefrom and extending into the casing member 50 in the same manner as in the previously described form.

A pulley 56 is secured on the end of the shaft 55 and connected by a driving belt 57 with an eccentric pulley 58 which is supported on the depending stub shaft 59. Downwardly extending eccentric portion 60 on the eccentric pulley 58 projects into a socket formation 61 in the connecting rod member 62 and is secured in rotatable relation

therein by the bearing formation 63. The pocket 61 is provided at one end of the connecting member 62, the other end of the connecting member 62 being vulcanized or otherwise secured in a resilient connecting block 64 which is provided on its lower face with a metal attaching plate 65 integrally secured thereto and fastened by means of screws 66 to the upper surface of the plate 67 which forms the upper portion of the rubbing shoe 52.

In operating this form of the machine the power shaft 55 rotates the eccentric pulley 58 by means of the pulley 56 on the shaft 55 and the connecting drive belt 57. Eccentric motion is transmitted from the pulley 58 to the connecting rod 62 by means of the eccentric portion 60 on the former which is rotatably connected with the end of the rod 62. Circular motion imparted to the free end of the rod 62 is transmitted through the block 64 to the rubbing shoe 52 against the resistance offered by the resilient posts 51 which connect the shoe 52 with the relatively fixed casing member 50. The resulting vibratory motion of the shoe 52 is irregular due to the resiliency of the connecting posts 51 and the connecting block 64. The motion of the shoe 52 at any particular time is influenced by the operative conditions previously described.

A further modified form of the rubbing machine is illustrated in Fig. 7. In this form of the device a downwardly opening supporting casing 70 is connected by resilient posts 71 with a rubbing shoe 72. A power driven shaft 73 is arranged to extend into the casing 70 and is connected by means of a pulley 74, secured on the end of the shaft 73, and a driving belt 75, with an eccentric pulley 76 which is supported on a depending stub shaft 77. The shaft 77 is positioned in relatively close relation to the pulley 74. An eccentric portion 78 on the pulley 76 extends into a recess or pocket 79 in a connecting plate member 80 and is rotatably secured therein by the bearing formation 81. The connecting plate 80 may be H-shaped and attached at four points to the rubbing shoe 72 by resilient connecting blocks 82. The recess or pocket formation 79 in the connecting plate 80 is located approximately in the geometrical center of the rubbing shoe 72 so that the center of movement of the latter coincides approximately with the center of rotation of the eccentric 76. The resulting vibratory motion in this form of the machine is variable in extent as well as in pattern because of the resiliency and location of the connecting posts 71 and the connecting blocks 82 and is determined by the operating conditions as previously described. The location of the connecting bearing for the eccentric in the geometrical center of the shoe is not restricted to this form of connecting bar or plate member. This principle for locating the bearing may be embodied in the other forms of the mechanism which are illustrated and described herewith.

In Figs. 8 and 9 there are illustrated alternative constructions for the connecting elements which secure the rubbing shoe to the supporting casing. Referring first to Fig. 8, the connecting element 90 comprises a length of resilient tubing 91, such as rubber or the like, having secured, by vulcanizing or other means, tapped metal blocks 92 and 93 in its opposite ends. At one end the connecting element 90 is secured to the upper wall 94 of the supporting casing 95 by means of a screw 96. At the other end the element 90 is secured to the plate member 97 of the rubbing shoe 98 by means of a screw 99. Resilient wire clamping rings 100 may be employed to insure that the tapped elements 92 and 93 will remain in position in the ends of the tube section 91. The resilient tubing 91 permits movement of the shoe 98 in any direction relative to the casing 95 while at the same time offering resistance to such movement.

In Fig. 9 a connecting element 101 is illustrated which comprises a section of coiled spring 102 and cap members 103 at opposite ends thereof to which the spring 102 is secured by welding or the like as indicated at 104. Each cap 103 is provided with a threaded center aperture 105 for receiving a securing screw. At one end the cap 103 is secured by screw 106 to the upper wall of the casing 107 and at the other end the screw 108 attaches the end of the element to the plate 109 of the rubbing shoe 110. A plurality of the elements 101 are arranged around the periphery of the shoe 110 and permit limited movement of the same in any direction relative to the casing 107.

While specific details of construction and specific materials have been referred to in describing the illustrated

forms of the invention, it will be understood that other details of construction and other materials may be resorted to within the spirit of the invention.

I claim:

1. In a rubbing machine, a downwardly opening rigid housing, a rubbing pad, flexible means depending within said housing and connecting said pad in spaced relation below said housing, said flexible means permitting a vibratory motion of said pad in any direction relative to said housing, a power driven shaft mounted in said housing and extending downwardly therein, an eccentric rotatably mounted in said housing, means connecting said eccentric and said shaft in driving relation, a generally Y-shaped bar member spaced above said pad, a bearing supported in said bar member intermediate the ends thereof and connecting said eccentric therewith, and flexible blocks connecting the ends of said bar member with said pad whereby when said power shaft is rotated an irregular vibratory motion will be imparted to said pad.

2. In a rubbing machine, the combination of a rigid support, a power shaft extending downwardly through said support, a driven member rotatably mounted on said support in spaced relation to said power shaft and connected in driving relation therewith, said driven member having a portion eccentric to its axis of rotation, a rubbing pad, flexible means connecting said rubbing pad to said support, an elongate bearing receiving member having end portions spaced above said rubbing pad, means independent of the means connecting the pad to the support for flexibly connecting the end portions of said bearing receiving member to said pad, a bearing positioned intermediate the ends of said bearing receiving member and connecting said eccentric portion on said power driven member thereto, whereby rotation of said power driven member causes said pad to vibrate relative to said support with a non-uniform motion.

3. In a rubbing machine, a supporting frame, a power driven shaft mounted in said frame, a rubbing pad, a plurality of resilient members connecting said pad to said frame in spaced relation to the end of said shaft, said resilient members being arranged in spaced relation around the margins of said pad, said resilient members connecting said pad to said frame for relative movement in all directions, a rigid Y-shaped arm, a flexible connection between the end of each leg of said Y-shaped arm and said pad, and means including an eccentric connecting said arm at a point intermediate the ends thereof in driving relation with the end of said shaft, the point of connection of said means with said arm being approximately in the geometric center of said pad, whereby upon rotation of said shaft said pad will be vibrated relative to said frame with an irregular motion.

4. In a rubbing machine, a relatively rigid supporting housing, a rubbing shoe, means connecting said shoe in spaced relation to said housing, said connecting means being flexible and permitting a limited vibratory motion of said shoe relative to said housing in any direction, a power shaft mounted in said housing and extending toward said shoe, an eccentric rotatably mounted in said housing, means connecting said eccentric and said power shaft in driving relation, a rigid member connected to said eccentric and movable relative to said housing upon rotation of said eccentric, and a flexible member spaced from said eccentric connecting said rigid member to said shoe independently of the means connecting the shoe to the housing, said flexible member permitting limited vibratory motion of said shoe relative to said rigid member in all directions whereby when said power shaft is rotated an irregular vibratory motion will be imparted to said shoe.

5. In a rubbing machine, the combination of a rigid support, a power driven member rotatably mounted on said support and having a portion eccentric to its axis of rotation, a rubbing shoe having a relatively rigid backing plate, a plurality of spaced flexible posts connecting said backing plate directly to said support for relative movement in any direction, a rigid Y-shaped bearing receiving member, a bearing positioned in said Y-shaped bearing receiving member and connecting said eccentric portion on said power driven member thereto and flexible connecting means between each leg of said Y-shaped bearing receiving member and the backing plate of said shoe, said flexible connecting means being independent of said flexible posts and permitting limited movement in any direction between said Y-shaped bearing receiving

member and said shoe upon movement of said bearing receiving member by rotation of said power driven member, whereby rotation of said power driven member will cause said shoe to vibrate relative to said support with an irregular motion.

6. In a rubbing machine, a supporting casing having a driven shaft mounted therein, a rubbing shoe having a relatively rigid backing member, means for connecting said casing and said rigid backing member, said shoe being positioned in spaced relation beyond the end of said shaft, said connecting means comprising a plurality of flexible post-like elements independently connected at opposite ends to said casing and said rigid backing member, said flexible elements being arranged in spaced relation around said shaft and adjacent the periphery of said shoe, said flexible elements permitting limited movement of said backing member relative to said casing in all directions and means independent of the casing and of said flexible elements connecting said rigid backing member and the end of said shaft, said last mentioned connecting means comprising an eccentric rotatably mounted in said casing, means connecting said eccentric and said shaft in driving relation, a rigid bar member spaced above said backing member, a bearing supported in said bar member and connecting the eccentric therewith and spaced flexible blocks connecting said bar member with said backing member at points spaced from said bearing whereby when said shaft is rotated an irregular vibrating motion will be imparted to said rubbing shoe.

7. A rubbing machine as recited in claim 6 wherein said flexible elements comprise coil spring members.

8. A rubbing machine as recited in claim 6 wherein said flexible elements comprise hollow flexible tubular sections having rigid connecting members at opposite ends for securing said elements to said casing and said pad, respectively.

9. A rubbing machine as recited in claim 6 wherein said flexible elements comprise solid rubber blocks having rigid connecting members at opposite ends for securing said elements to said casing and pad, respectively.

10. In a rubbing machine, a supporting frame, a power driven shaft mounted in said frame, a rubbing pad, a plurality of relatively flexible members connecting said pad to said frame adjacent the end of said shaft, said flexible members being arranged in spaced relation around the margin of said pad whereby said pad is connected to said frame for movement relative thereto in any direction, a rigid elongate arm, means including an eccentric connecting one end of said arm in driving relation with the end of said shaft and flexible means adjacent the other end of said arm connecting said arm with said pad independently of said flexible members whereby upon rotation of said shaft said pad is vibrated with an irregular motion.

11. In a rubbing machine, a supporting frame, a power driven shaft mounted in said frame, a rubbing pad having a relatively rigid backing member, a plurality of resilient post members connecting said backing member to said frame adjacent said shaft, said resilient post members being arranged in spaced relation adjacent the margin of said backing member and providing for movement of said backing member relative to said frame in any direction, an elongate rigid arm member, flexible means connecting opposite ends of said arm member to said backing member, said flexible means being independent of said resilient post members and providing for movement of said backing member relative to said arm member in any direction, and means including an eccentric connecting said arm member intermediate its ends in driving relation with said shaft, the connection of said last mentioned means with said arm member providing for eccentric movement of said arm member upon rotation of said shaft.

12. In a rubbing machine, a downwardly opening rigid housing, a rubbing pad having a relatively rigid backing member, flexible means extending within said housing and connecting said backing member in spaced relation to said housing, said flexible means permitting a vibratory motion of said pad in any direction relative to said housing, a power driven shaft mounted in said housing and extending downwardly therein, an eccentric rotatably mounted in said housing, means connecting said eccentric and said shaft in driving relation, a rigid yoke member extending longitudinally in spaced relation above

said backing member, a bearing supported in said yoke member adjacent one end thereof and connecting said eccentric therewith, and laterally spaced flexible blocks adjacent the other end of said yoke member and connecting said yoke member to said rigid backing member independently of the means connecting said backing member to said housing whereby when said power shaft is rotated an irregular vibratory motion will be imparted to said pad.

13. In a rubbing machine, a relatively rigid supporting housing, a rubbing shoe having a relatively rigid backing member, means connecting said backing member in spaced relation to said housing, said connecting means being flexible and permitting a limited vibratory motion of said shoe relative to said housing in any direction, a power shaft mounted in said housing and extending toward said shoe, a rigid plate-like connecting member positioned between said housing and said shoe in spaced relation to said backing member, means including an eccentric connecting one face of said rigid connecting member in driving relation with the end of said power shaft and flexible means connecting the opposite face of said rigid connecting member with said backing member independently of the means connecting said backing member to said housing whereby upon rotation of said shaft an irregular motion will be imparted to said shoe.

14. In a rubbing machine as recited in claim 13, wherein said means connecting said backing member to said housing consists of a plurality of post-like members of resilient material which are each connected at the opposite ends thereof to the housing and the backing member, respectively, and which are spaced around said power shaft and adjacent the periphery of said backing member.

15. In a rubbing machine, a relatively rigid supporting housing, a rubbing shoe, a plurality of post members connecting said shoe in spaced relation to said housing, said post members being of generally circular cross section and being formed of relatively flexible material to permit a limited vibratory motion of said shoe relative to said housing in any direction, a power shaft mounted in said housing and extending toward said shoe, an eccentric rotatably mounted in said housing, means connecting said eccentric and said power shaft in driving relation

tion, a rigid member connected to said eccentric and movable relative to said housing upon rotation of said eccentric, and a flexible member spaced from said eccentric connecting said rigid member to said shoe, which flexible member is independent of the post members connecting the shoe to the housing, said flexible member permitting limited vibratory motion of said shoe relative to said rigid member in all directions whereby when said power shaft is rotated an irregular vibratory motion will be imparted to said shoe.

16. In a rubbing tool, a relatively rigid supporting housing, a rubbing shoe, means connecting said shoe to said housing for vibratory movement of said shoe in a plane which is spaced in predetermined relation to said housing, said connecting means comprising a plurality of peripherally spaced cylindrical post members, which post members are formed of relatively flexible material and which are secured at their opposite ends to said housing and shoe, respectively, said post members permitting limited vibratory motion of said shoe relative to said housing in any direction in said plane, a power shaft mounted in said housing and extending toward said shoe, an eccentric rotatably mounted in said housing, means connecting said eccentric and said power shaft in driving relation, a rigid member connected to said eccentric and movable relative to said housing upon rotation of said eccentric and means connecting said rigid members to said shoe whereby when said power shaft is rotated a vibratory motion will be imparted to said shoe.
